UNITED STATES PATENT OFFICE.

MICHAEL SMART AND THOMAS W. GAYNOR, OF NEW YORK, N. Y.

IMPROVEMENT IN SAFETY-VALVES.

Specification forming part of Letters Patent No. 129,991, dated July 30, 1872.

Specification describing a new and Improved Safety-Valve, invented by MICHAEL SMART and THOMAS W. GAYNOR, of New York city, in the county and State of New York.

The drawing represents a vertical central section of our improved safety-valve.

Similar letters of reference indicate corresponding parts.

This invention has for its object to so arrange a safety-valve for steam-boilers that it will be sensitive to the action of the steam, and not liable to become obstructed. This invention consists in providing the valve-chamber with escape-steam ports and with a chambered extension, in which is arranged a spiral spring that acts through the medium of a collar and piston-rod to partly hold the piston against the pressure of steam in the boiler, as will be hereinafter described.

A in the drawing represents the valve-chamber, of cylindrical form and secured in a vertical position upon a steam-boiler. a is the steam-pipe leading from the lower part of the chamber A to the engine. b is the steam-escape pipe projecting from the chamber A at a somewhat greater height than the pipe a. B is the valve, made in shape of a piston, which fits the chamber A with exactness. It is suspended from a stem, d, which is weighted on top. In an upper chamber, e, through which the stem d also extends, said stem carries two shoulders, f and g, the lower being fast, the upper loose on it, and a coiled spring, h, between the two. The spring h, together with the weight i on top, serves to so far lower the valve that the

shoulder g rests on the bottom of the chamber e. In this position the valve effectually shuts the escape-pipe, as shown, and also the entrance j to a circular steam-chamber, l, which, embracing the chamber A, leads to the pipe b. As soon as the steam-pressure overcomes that of the weight and spring the valve will be raised to blow off the steam directly through b, and also through j l b. By screwing down the top m of the chamber e, lowering the loose shoulder f, and contracting the spring h, or by adding to the weight on the top of the stem, the valve will be adapted to resist greater steam-pressure. By making a flanged opening for the pipe which conveys the steam from the boiler to the engine a part of the safety-valve chamber, we save cutting the usual hole in the boiler for that purpose.

Having thus described our invention, we claim as new and desire to secure by Letters Patent—

1. The valve-chamber A provided with the chambered extension e, pipes a b, and parts j l, all constructed as shown and described, for the purpose specified.

2. In combination with the foregoing, the solid piston B, piston-rod d, collars g s, and spring h, all constructed in the manner and for the purpose specified.

MICHAEL SMART.
THOMAS W. GAYNOR.
